UNITED STATES PATENT OFFICE.

ARTHUR W. HANDFORD, OF EVANSTON, ILLINOIS, ASSIGNOR, BY MESNE ASSIGNMENTS, TO AMERICAN SEAMLESS CONTAINER COMPANY, OF ST. CHARLES, ILLINOIS, A CORPORATION OF DELAWARE.

METHOD OF FORMING FIBROUS-PULP PAILS, RECEPTACLES, AND OTHER ARTICLES.

1,407,409.

Specification of Letters Patent. Patented Feb. 21, 1922.

Application filed January 18, 1918. Serial No. 212,386.

To all whom it may concern:

Be it known that I, ARTHUR W. HANDFORD, a citizen of the United States, residing at Evanston, in the county of Cook and State 5 of Illinois, have invented certain new and useful Improvements in Methods of Forming Fibrous-Pulp Pails, Receptacles, and other Articles, of which the following is a specification.

10 This invention relates to the method of forming pails and other articles and receptacles, and more particularly to such method whereby these and seamless pails and covers therefor are formed of compressed fibrous 15 pulp.

Among the objects of my invention is to provide a new method of manufacturing seamless pails and other articles and receptacles of compressed fibrous pulp; further 20 to increase to the maximum the speed, economic and general efficiency possible in the manufacture of the same; further to render such operations and steps continuous whereby the pulp stock may be fed in at one 25 end of the apparatus and the formed pails, covers or other articles may be continuously removed from the other end; further to render possible the removal of foreign substances from the "half-stuff," further to 30 provide for washing and sterilizing the fibres of the pulp; further the addition of a suitable sizing material to the pulp whereby to strengthen the pails or other articles or receptacles and render them moisture and temperature 35 resistant; further to effect the elimination of excess water from the pulp prior to passing into the presses; further to provide for the regulation of the entry of the pulp into the presses so as to give just the 40 required amount for forming a pail, cover or other articles as desired; further to provide at the output end of the mechanism a continuous conveyer by means of which the formed pails or other articles can be quickly 45 and easily transferred from the presses to the drying room; further to provide means whereby the greater part of the surplus pulp not consumed in the presses for forming the articles will be returned to one of the stuff 50 chests; and such further objects, advantages and capabilities as will later more fully appear.

In the accompanying drawings I have

illustrated a preferred arrangement of apparatus for carrying into effect my new 55 method. However, I desire the same to be considered as illustrative only and not as limiting the scope of my invention.

Referring to the drawings:

Figure 1 is a diagrammatic plan view of 60 one form of apparatus for carrying into effect my improved method.

Figure 2 is a transverse vertical sectional view taken through the pulping machine.

Figure 3 is a fragmentary sectional view 65 through the stuff chest 6, showing the arrangement of pipe in the bottom thereof whereby foreign substances may be separated from the pulp.

Figure 4 is an elevation of one form of 70 water eliminating device which may be applied between the feeding chests and the presses.

Figure 5 is a vertical longitudinal sectional view through Figure 4. 75

Before taking up a detailed description of the apparatus shown in the drawings a short general statement of the steps employed in forming the pulp and pails will be given.

The pulp stock is first run through a 80 shredding machine or any other suitable machine which tears the stock into strips or shreds. From thence it goes into a pulper or any other suitable machine which removes foreign substances and masticates the stock 85 with water and sterilizes it with steam. After the stock has been thus treated, it is known as "half-stuff." In this pulping machine, the larger and more prominent foreign substances are removed. Then the 90 "half-stuff" is dropped, pumped or conveyed into an agitated stuff chest which is so constructed that the remaining foreign substances may be easily removed. The "half-stuff" is then dropped, pumped or conveyed 95 to beaters or refining engines where it is thoroughly pulped, washed, sterilized with steam and sized. The pulp is then dropped, pumped or conveyed into other agitated stuff chests, where a constant supply is kept. 100 From the last mentioned stuff chest it is dropped, pumped or conveyed into feeding chests connected with which, by means of pipes or conduits are power devices which eliminate the surplus water from the pulp, 105 reducing it to any required consistency and

also which power devices inject the pulp into the wells of the forming presses in desired amounts. The elimination of water and feeding of presses may or may not be 5 performed automatically with the operation of the presses as desired. Also each one of the water eliminating and pulp injecting devices may feed one, two or any greater number desired of the forming presses.

10 Referring to the apparatus illustrated in the drawings, S represents a shredding machine of any suitable design. The pulping machine through which the stock material next passes comprises the hopper 1, having 15 sloping sides 1', and the main body 2 in which rotate suitable arms 3, mounted upon the shaft 4, which shaft is driven by any suitable source of power applied to the drive wheel 5. This pulping machine is so positioned relative to the agitated stuff chest 6 that as the "half-stuff" emerges from the pulping machine, it will be suitably conveyed by dropping, pumping or otherwise into this stuff chest. The pulping machine 20 at a point below the hopper is provided with a downwardly extending portion forming the well or chamber 54 hinged across the lower edges 55 of which, by means of the hinge 56 is the door 54' which door may be 25 suitably secured in closed position by any convenient form of latch. By releasing such latch the door may be swung downwardly to permit the cleaning of the well and the removal of foreign substances which 30 have dropped thereinto. The stuff-chest is so constructed that the "half-stuff" may be agitated therein and as seen in Figure 3, the pipe 8 leading from this stuff chest is positioned with its upper end a substantial dis- 35 tance above the bottom of the chest whereby to permit the remaining foreign substances to settle through the soft "half-stuff" to the bottom of the chest and below the open end of the pipe 8 from which position 40 it may be later removed in any appropriate manner.

45 In the pipe line 8 and adjacent the stuff chest 6 is located the valve 9, and at a suitable distance from the valve 9 the pipe 8 leads into the stuff pump 7. The stuff pump 50 7 is connected with the beaters or refining engines 11 and 12 by means of the pipe 10, the entry of pulp into the beaters 11 and 12 being controlled by suitable valves 13 and 55 14. The beaters 11 and 12 are each provided with the central partitions 15 and 16, the ends of which are spaced from the ends of the beaters and around which partitions and through the open ends thereof may circ- 60 ulate the mass of pulp. Suitably mounted for rotation upon one side upon each of these partitions are the usual drums 17 and 18 which are driven by means of the drive wheels 19 and 20 and which assist in a well 65 known manner in the further treatment of

the pulp. It is obvious that instead of making use of the particular pump arrangements shown that the "half-stuff" may be dropped, pumped or conveyed from the stuff chest 6 to the refining machinery in any 70 suitable manner. Also in place of the beaters 11 and 12, I may if desired make use of any other forms of refining engine suitable for the necessary treatment of the pulp.

75 Connecting the beaters 11 and 12 with the further stuff chests 22 and 23 is the pipe line 21, having suitable connections with the bottom of each of the beaters and stuff chests. These further stuff chests are so constructed that the pulp may be suitably agitated there- 80 in and in which chests a constant supply of the pulp may be kept. Connected with the stuff chests 22 and 23 by the pipe lines 24 and 25 are stuff pumps 28 and 29; the flow of pulp through the pipes 24 and 25 being 85 controlled by suitable valves 26 and 27. From the pumps 28 and 29 leads the pipe line 30 which is extended around the loop 31 and into feeding chests 32 and 33. The pumps 28 and 29 may be driven by any suit- 90 able source of power applied to the drive wheels 34 and 35.

95 Connected with the feeding chests 32 and 33 by means of the pipes 36 and 40 are the water eliminating devices A which are suitably located in position over the pail presses 38, 39, 42 and 43, the construction of which water eliminating devices will later more fully appear. In the pipe line 30, 31 and beyond the feeding chest 33 is located the branch connection 44 from which leads the pipe 45 and the branch pipe 46; the pipe 45 leading into the stuff chest 23 and the branch pipe 46 leading into the feeding chest 47, connected with which by means of pipe 48 100 is a water eliminating device A, which feeds the pulp in desired quantities and of the desired consistency into the cover presses 50 and 51 in a manner similar to that referred to in connection with the forming presses, 105 which form the pails, covers or other articles or receptacles.

110 Located adjacent the forming presses are the continuous conveyors 52 and 53 to which the pail covers, receptacles or other articles 115 may be readily transferred from the presses and conveyed thereon into the drying room, where they are dried and hardened and given their final set, and from which they are conveyed to receive their final finish.

120 Referring to Figures 4 and 5, it will be seen that the water eliminating device A comprises the body 60 in which are formed the enlarged annular portions 61 and 62. Upon the top of the body 60 and leading 125 thereinto is the pipe 63 which connects with the pipes 36, 40 and 48 respectively. Mounted within the body portion 60 for longitudinal sliding movement therein is the piston head 64 carried by the piston rod 65. At 130

each end of the water eliminating device are provided the spouts 66 and 67 which spouts are adapted to be placed over the forming presses in order to guide the pulp thereinto.

5 Located within the body 60 and extending across the space formed by the annular portions 61 and 62 are screens 68 and 69, while from the bottom of the spaces 72 and 73 formed between the screens and the outer 70 shell of the portions 61 and 62 are the drain pipes 70 and 71. At each end of the water eliminating device is formed an adjustable pressure resisting door 74 which will be so constructed as to resiliently resist pressure 75 from the inside and which resistance may be regulated and controlled either by hydraulic, air, steam or other mechanical power and operated by valve or lever, the details of which mechanism is not shown herein.

10 From an inspection of the drawings it will be seen that in carrying out my improved method by means of the apparatus disclosed therein the stock material such as old paper and the like will first be run through the 80 shredding machine S, and after being sufficiently shredded therein, it will be conveyed into the hopper 1 of the pulping machine 2 by any suitable means. In the pulping machine the stock material will be masticated 85 with water and sterilized with steam and converted into what is known as "half-stuff" as pointed out above. Any foreign materials heavier than the "half-stuff" will fall into the well or chamber 54 at the bottom of the 90 pulping machine (see Figure 2), from which they may be later removed. From the pulping machine the "half-stuff" will be dropped, pumped or conveyed into the stuff chest 6 where it will be further agitated and the remaining foreign particles collected in the bottom of this chest as pointed out above in connection with Figure 3. From the stuff chest 6, the "half-stuff" is dropped, pumped or conveyed to the beaters or refining engines 11 and 12 where it will be thoroughly 95 pulped, washed, sterilized with steam and sized with rosin and alum or other suitable material. The addition of such sizing when made use of results not only in strengthening the finished pail or cover, but also renders the same more resistant to water, temperature and the like. After being sufficiently treated in the beaters, the pulp will be dropped, pumped or conveyed into the further stuff chests 22 and 23 where it may be 105 further agitated and in which stuff chests may be maintained a constant supply. From the stuff chests 22 and 23, the pulp will be conveyed through the pipe line 30, 31 into the feeding chests 32, 33 and 47 and from these feeding chests through the pipes 36, 40 and 48 respectively into the water eliminating devices A. These water eliminating devices may or may not, as desired, be made 110 to operate automatically with the operation of the presses. The pulp, upon entering the water eliminating device through pipe 63, will be forced towards one end of this device by movement in that direction of the piston 64 and accordingly squeezed between the piston and the pressure resisting door 74, the result of which will be to force the surplus water from the pulp through the screen 68 and out through the drain 70. The resistance of the door 74 will be so regulated that 115 the pulp will be brought to the desired consistency by the elimination of water therefrom and when this point is reached the door will be so regulated that the pressure from within will cause the same to open and eject 80 a desired amount of pulp from within the water eliminating device and feed the same through the hopper 66 into the adjacent press. While the piston 64 is in operation at one end of the water eliminating device, 85 pulp will be entering through the pipe 63 into the other end for compression and similar treatment upon the return stroke of the piston. It is obvious, of course, that this water eliminating device may be constructed 90 to operate in connection with two presses or only one as desired.

120 From the arrangement of the pipe line 30, 31 and 45, it will be seen that a continuous flow of pulp may be effected from the stuff chest 22 and around and back into the stuff chest 23, thus giving a continuously fresh supply of pulp to be fed through the pipes 63 and from the water eliminating device into the presses. After the pails, covers 100 or other articles have been formed in their respective presses, they will be removed therefrom and transferred to the continuous conveyer lines 52 and 53 and carried thereon into an adjacent drying room, where the 105 articles are subjected to heat thoroughly set, dried and hardened and then it is completely finished into condition for commercial use. It is obvious that during its passage around the pipe line 30 and 31, the necessary 110 amount of pulp for feeding the cover presses 50 and 51 will be diverted into the pipe line 46 by reason of the branch connection 44. The surplus pulp over that being fed into the presses will be returned 115 through the pipe line 45 into the stuff chest 23 as the result of which the pulp will be continuously kept in a fresh condition.

125 By this process the completion of a seamless thoroughly strong, heat resisting, moisture repellent pail, cover receptacles or other article is accomplished in a practically automatic manner.

It will be seen from the above that by my improved method the manufacture of pails, 125 receptacles, covers and other articles carried on in a continuous operation and effected in a much more efficient, economical and convenient manner. Also in carrying out my method it is not essential that the steps 130

above described should be carried out in the order which I have described, it being obvious that certain changes could be made therein without departing from the inventive idea.

Having now described my invention, I claim:—

1. The method of forming seamless compressed fibrous pulp pails which consists in 10 passing the pulp into a plurality of stuff chests, selectively drawing said pulp from said stuff chests and passing it into one or more feeding chests, transferring the pulp from said feeding chests to a pail press 15 where it is pressed into pails, also transferring some of said pulp to a cover press where it is pressed into covers, removing said pails and covers onto a continuous conveyor for transportation to a drying room, 20 and returning the surplus pulp to one of said stuff chests.

2. The method of forming seamless compressed fibrous pulp pails which consists in thoroughly comminuting the stock material 25 and reducing it to a pulp by passing it through a pulper, stuff chest, and refining engines, then transferring it to a further stuff chest, from whence it is conveyed to a feeding chest, passing it from said feeding chest 30 to a pail press where it is pressed into pails, conveying a portion of the pulp to a cover press where it is pressed into pail covers, returning the surplus pulp from said presses back to said further stuff chest, and removing 35 the pressed pails and covers from said presses onto a continuous conveyor by which they are carried to the drying room for completion by drying.

3. The method of forming seamless compressed fibrous pulp pails which consists in 40 thoroughly reducing the stock material to a pulp by passing it through a pulper and series of refining engines, then transferring it to a plurality of stuff chests, passing said 45 pulp from said stuff chests to pail presses and cover presses, returning the surplus pulp to said stuff chests, and transferring by means of a continuous conveyor the pails and covers from said presses to a drying 50 room.

4. The method of forming seamless pails of compressed fibrous pulp which consists in passing the stock material through a shredding machine and from thence into a 55 pulping machine, reducing said stock to a pulp in said pulping machine and sterilizing it therein with steam, transferring said stock from thence into an agitated stuff chest, conveying the pulp from said stuff chest and delivering it into a refining apparatus, where it is thoroughly pulped, washed, sterilized with steam and sized, transferring said pulp from said refining apparatus to a plurality of stuff chests, where it is further agitated and

kept at a constant supply, selectively transferring said pulp from said last mentioned stuff chests to a battery of feeding chests, then removing the excess water and feeding it in predetermined quantities to a plurality of pail and cover presses, pressing pails and 70 covers in said presses, returning the pulp not consumed in said presses to one of said last mentioned stuff chests, and then transferring by means of a continuous conveyor said pails and covers from said presses to 75 a drying room where they are completed by drying.

5. The method of forming seamless compressed fibrous pulp pails which consists in 80 selectively drawing the pulp from a plurality of stuff chests and passing it through a conduit system, from which it may be fed as desired into any one or more of a battery of pail and cover presses, pressing pails and covers in said presses, transferring said 85 pails and covers from said presses to a continuous conveyor for removal to a drying room, and returning the pulp not used in said presses back to one of the stuff chests from which it was drawn. 90

6. The method of forming seamless compressed fibrous pulp pails which consists in 95 positively and continuously circulating the pulp from either one or all of the plurality of stuff chests through a closed conduit system and back to one of said stuff chests, and during such circulation selectively withdrawing from said conduit system pulp to be fed into one or more presses, pressing pails in said presses, and drying said pails. 100

7. The method of forming seamless compressed fibrous pulp pails which consists in 105 positively and continuously circulating pulp from one or more stuff chests through a closed conduit system and back to one of said stuff chests, withdrawing during such circulation pulp from said system, transferring it to one or more presses, and pressing it into pails in said press or presses. 110

8. The method of forming seamless compressed fibrous pulp pails which consists in 115 transforming stock material into pulp and passing it into one or more stuff chests, circulating said pulp from said stuff chests through a conduit system and back into one of said stuff chests, withdrawing during circulation a portion of said pulp from said system and passing it into pail presses and pressing it into pails, also withdrawing pulp from said system and passing it into cover 120 presses and pressing it into covers, and transferring said pails and covers from said presses onto a continuous conveyor for removal to a drying room.

9. The method of forming seamless compressed fibrous pulp pails which consists in 125 masticating the pulp stock in a pulping machine and passing it into a stuff chest, then

- passing the pulp thus formed through one or more refining engines and into one or more further stuff chests, circulating said pulp from thence through a conduit system and back into one of said further stuff chests, and withdrawing during said circulation portions of said pulp and transferring it into presses, and pressing said withdrawn pulp into pails in said presses.
10. 10. The method of forming seamless compressed fibrous pulp pails which consists in masticating the pulp stock with water in a pulping machine and passing it into a stuff chest, then passing the pulp thus formed through one or more refining machines and into one or more further stuff chests, circulating said pulp from thence through a conduit system, and back into one of said further stuff chests, withdrawing during said circulation portions of said pulp and transferring it into presses, pressing said withdrawn pulp into pails and covers in said presses, and transferring said pails and covers on a continuous conveyor from said presses to a drying room.
11. The method of forming seamless compressed fibrous pulp pails which consists in masticating the stock material in a pulping machine and removing the heavier foreign substances therefrom while in said machine, then passing the material into an agitated stuff chest and further separating foreign substances therein, further treating the pulp material in refining machines and stuff
- chests, and then feeding the pulp into 35 presses to be formed into pails and covers.
12. The method of forming seamless compressed fibrous pulp pails, which consists in reducing the stock material to thoroughly prepared pulp, and during such reduction 40 washing and sterilizing the fibers thereof, and removing the heavier foreign substances therefrom, passing the pulp into one or more stuff chests, circulating it through a conduit system back to said stuff chests, 45 withdrawing pulp from said conduit during said circulation, passing said withdrawn pulp into presses, and pressing the same into pails and covers, said steps being carried out in continuous and uninterrupted opera- 50 tion.
13. The method of forming seamless compressed fibrous pulp receptacles, which consists in positively and continuously circulating pulp from one or more stuff chests 55 through a closed conduit system, and back to one or more of said stuff chests, withdrawing during such circulation pulp from said system, transferring it to presses, and pressing it into a receptacle.
- In witness whereof, I hereunto subscribe my name to this specification in the presence of two witnesses.

ARTHUR W. HANDFORD.
